UNITED STATES PATENT OFFICE.

EDWARD CHARLES DAVIS AND THOMAS BALDWIN, OF LONDON, ENGLAND.

TELESCOPIC JOINT.

SPECIFICATION forming part of Letters Patent No. 445,410, dated January 27, 1891.

Application filed August 2, 1890. Serial No. 360,827. (No model.) Patented in England July 17, 1890, No. 11,156.

To all whom it may concern:

Be it known that we, EDWARD CHARLES DAVIS, gentleman, a subject of the Queen of Great Britain, residing at Penrith House, 5 190 Peckham Rye, London, England, and THOMAS BALDWIN, engineer, a subject of the Queen of Great Britain, residing at 20 Ivydale Road, Nunhead, London, England, have invented certain Improvements in the Method 10 of Constructing and Locking Telescopic Joints, and in the application of the same to various useful purposes, (for which we have obtained a patent in Great Britain, No. 11,156, bearing date July 17, 1890,) of which the following is a specification.

This invention relates to the telescopic joints for rods, tubes, billiard-cues, telescopes, music-stands, and other articles; and the invention consists in the features of construction 20 and the combination or arrangement of parts hereinafter described and claimed, reference being made to the accompanying drawings, in which—

Figure 1 is a broken sectional elevation of 25 the improved joint. Fig. 2 is a section on the line 1 2, Fig. 1. Fig. 3 is a plan view of the end collar or cap. Fig. 4 is an elevation, partly in section, of the operative part of the device. Fig. 5 is a section on the line 3 4, 30 Fig. 1. Fig. 6 is a plan of the gripping-fingers, and Fig. 7 is an elevation of the inner ring.

In the drawings, the letter *a* indicates the inner sliding tube; *b b'*, collars formed upon 35 or attached to the inner tube *a*; *c c*, double saw-kerfs, which allow the collar *b* to expand and act as a steadyng-collar; *d*, the outer tube, in which the collars *b* and *b'* with the tube *a* slide freely. The letter *e e'* indicates a short 40 tube, one end of which is formed with tapered gripping-fingers *e e*. The tube *e'* is soldered to the tube *d*, as shown in the drawings. The lower edge *k* of this tube forms a shoulder to prevent the accidental withdrawal 45 of the tube *a*, the contact of the collar *b'* with the shoulder *k* preventing such withdrawal. *ff* are two inclined or helical slots cut through the tubes *d* and *e'*. *g* is a collar partly formed to fit the outside of the tube *d*, its outer end 50 being tapered so as to act as a wedge upon the tapered gripping-fingers *e e* when required, and thereby cause them to grip the tube *a* and lock it in any required position.

h h are two lugs pivoted to the collar *g* at *h' h'*. These lugs slide in the slots *ff* when the 55 collar *g* is turned by hand, and thereby raise or lower the collar *g*. The letter *i* indicates any suitable external covering for the tube *d*. *m* is a collar for securing the material forming the covering marked *i*, and *n* is a cap for a 60 similar purpose, having perforations marked *o* to reduce weight.

From the foregoing it will be understood that by turning the coned collar *g* in the direction of a right-hand screw the coned collar travels downward, and this motion causes the conical portion of the collar to compress the gripping-fingers *e e*. The friction arising from this compression firmly locks the tube *a* in any required position. By turning the collar *g* in the opposite direction it recedes from the gripping-fingers *e e*, and thus removes the frictional contact with the inner tube *a*. The tube *a* may be then drawn outward or pushed inward, as required, and again locked, as before described.

In adapting our invention to billiard-cues the tube *a* is extended to the usual length by means of a light tapered rod of the usual form fitted to its outer end; but such billiard-cues possess the additional advantage of being adjustable in length.

Our invention is applicable to many articles which require telescopic and locking action, and to any number of joints in the same 85 article.

Having thus described our invention, what we claim is—

In the construction of telescopic joints, the combination, with the tubes to be joined, of 90 a coned collar provided with studs engaging with inclined slots in the larger tube, and a series of gripping-teeth formed on the end of the larger tube and adapted to be pressed by the coned collar against the smaller tube, 95 substantially as described.

Dated this 18th day of July, 1890.

EDWARD CHARLES DAVIS.
THOMAS BALDWIN.
